HANDLE FOR SCREW DRIVERS AND
SIMILAR TOOLS

Joseph Martin Hadfield, Chicago, Ill.

Application June 11, 1948, Serial No. 32,501

1 Claim. (Cl. 145—61)

2

The present invention relates to screw drivers and similar tools, and is particularly concerned with the provision of improved tools which will enable the user to drive home threaded members more quickly and efficiently than with the devices of the prior art.

One of the objects of the invention is the provision of an improved screw driver or similar tool in which the small metal shank of the screw driver or other tool is suitably roughened so that it may be grasped between the thumb and forefinger or middle finger of the hand and twirled at a high speed with a minimum amount of effort.

While there are screw bolts and other threaded members, the threads of which may be damaged or rusted or ill fitted so that the turning is difficult, most screw bolts and other threaded members turn easily until they reach the point where they begin to tighten on the subject-matter they are intended to secure. Many mechanics turn a screw bolt by hand until it reaches the tightening position, but that is a slow and laborious process.

Another object of the present invention is the provision of improved screw drivers and other tools, by means of which a screw bolt or other threaded member can be spun at a high speed until the screw bolt begins to tighten, after which it may be tightened in the usual way.

Another object of the invention is the provision of an improved screw driver or other tool, the shank of which is knurled so that the shank can be spun between the fingers, and the head of which is suitably shaped and of such size that it can be permitted to slide in the palm as the fingers spin the shank. Thus the palm is adapted to guide the head of the screw driver like a bearing while the fingers are located to spin the shank and drive the screw home to the tightening position, with a minimum of labor and in a minimum length of time.

Other objects of the invention will be apparent from the following description and the accompanying drawings, in which similar characters of reference indicate similar parts throughout the several views.

Referring to the single sheet of drawings accompanying this specification,

Fig. 1 is a view in perspective of an ordinary screw driver embodying the invention;

Fig. 2 is a view in perspective of the invention embodied in a small socket wrench;

Fig. 3 is a view in perspective of another modification in which the driving end of the screw driver is cruciform;

Fig. 4 is a fragmentary view in perspective of

another modification in which sockets of different size may be applied to the shank; and

Fig. 5 is another view in perspective of a modification in which the shank is provided with a knurled insulating sleeve for electrical work.

Referring to Figure 1, 10 indicates in its entirety a screw driver embodying the invention, in which the shank 11 is provided with an integral flattened end portion 12, having a narrow edge portion 13 adapted to be received in the kerf of a screw.

The shank 11 has its opposite end flattened or squared at 14 and suitably anchored in a round knob 15, which may consist of any suitable material. In the preferred embodiment of the invention, knob 15 may be molded out of an initially plastic composition, such as a vinyl chloride resin, methyl methacrylate, polystyrene or the like.

20 The shank 14 may have an integral square part 16 imbedded in the molded head. The head 15 may be of any desired shape, but is preferably round and small enough to be held in the palm of the hand, as shown in Figure 1, when the 25 thumb and the middle finger reach down past the handle into engagement with a knurled portion 17 of the shank.

The knurled portion 17 of the shank is preferably relatively long so that the fingers of the 30 user may be applied at various points of the shank for the purpose of spinning the shank.

Various types of knurling may be applied, but the preferred form may consist of helically extending grooves and ridges crossing each other, 35 leaving raised isolated islands or lands between the crossing grooves, by means of which the fingers can get a firm grip on the shank.

Referring to Figure 2, in this case the shank and knob may be substantially as described with 40 respect to Figure 1, but the end of the tool shank 11 is provided with an integral enlargement 18, formed with an integral wrench socket 19. The wrench socket 19 is preferably relatively deep, and while it may be of any suitable shape, such as rectangular, hexagonal, it may also be hexagonal with intermediate corners for receiving a hexagonal nut.

The socket wrench of Figure 2 may be most popular with users who are assembling small machine parts where machine screws are used instead of the screws having screw driver kerf.

The socket 19 is preferably made relatively deep so that it may be used to drive nuts home while the bolt to which the nut is applied projects upward into the socket.

Referring to Figure 4, this is a modification of Figure 2, in that this shank 11 is provided with a squared end portion 20 for receiving a removable socket head 21, having a squared aperture 22 for receiving the squared end 20.

A spring pressed ball 23 engages in a groove 24 on the squared portion 20 to hold the removable socket on the shank. The socket head 21 has the usual hexagonal socket 25 in its opposite end, and a plurality of socket members 21 of different sizes may thus be applied to the same shank 11.

Referring to Figure 3, this is a modification in which the shank 11 and knob 15 may be substantially as described with respect to Figure 1, but at the opposite end the shank 11 carries a cruciform screw driving formation 26 of the type known in the trade as the "Phillips" screw driver. Thus the present invention may be applied to screw drivers and socket wrenches of all different types.

Referring to Figure 5, this is a modification similar to Figure 1, except that the shank 11 is provided with a thin electrically insulated sleeve 27, the surface of which is knurled like the surface 17 of Figure 1. The sleeve 27 may consist of an initially plastic composition in which the shank is dipped or which is molded on the shank and provided with the knurled formations.

In another form of the invention, a resilient rubber sleeve may be so constructed that it stretches tightly about the shank of the screw driver, adhering closely to it and giving the shank a rubber covering. This rubber sleeve may not require any knurled surfacing as the rubber itself may be of such characteristics as to give a nonslip grip with the fingers.

The use of my screw drivers and socket wrenches is as follows: The knurled surface is intended to be employed when a nut or a screw is to be driven, and has to be rotated some distance during which it turns freely before engaging the part to be secured.

In such case the screw driver, for example, can be applied to the screw and the shank 11 can be spun between the fingers which are applied to the roughened surface 17 or 27. Since the screw or nut turns freely at this time, a single spin will drive it to the point where it begins to bind, thus saving the tedious hand-turning of the knob of the screw driver, and reducing the time and labor required in applying and tightening nuts and screws.

After the nut or screw has reached the point where it begins to bind, the hand of the user being over the knob 15, the knob may be gripped and used to turn the screw driver or the tool to drive the screw or nut home and tighten it.

It will thus be observed that I have invented an improved structure for screw drivers and other tools in which the shank may be grasped between the fingers and caused to spin to turn the nut or screw as long as it turns freely, while the knob is still available to tighten the screw or for any other purpose such as the loosening of a tight screw.

My tools will save a great deal of time on the

part of mechanics and permit the driving of screws and other threaded members with still greater ease than any other tool so far devised of which I am aware.

While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters Patent of the United States, is:

In a hand tool adapted for twirling with the fingers under loose conditions and for forceful use of the handle to tighten a threaded member, the combination of an elongated, slender, cylindrical metal shank having a tool formation located at its working end and having a noncircular integral head carried by its other end, an integral small size knob in which said noncircular head is imbedded to prevent relative rotation between said entire knob and shank, the said knob having a relatively short cylindrical portion which is shorter axially than its diameter and its diameter being less than the distance between the rear portion of the fingers and thumb of the user when arcuately shaped for twirling motion, said cylindrical portion being provided with a tapered smaller portion surrounding said shank, the total length of said knob being substantially less than twice its diameter and less than the distance from the palm of the hand of the user to the end of the fingers, said shank having a frictional finger gripping surface adjacent said knob to prevent relative slippage between the fingers of the user and said shank, said knob because of its small size and shape being rotatable in the palm of the user when the shank is twirled between the thumb and fingers by the user to drive a loose threaded member speedily to its place, the knob then being used to tighten the threaded member in a minimum amount of time through frictional contact with the palm of the user, without changing the hand position of the user relative to the tool.

JOSEPH MARTIN HADFIELD.
